UNITED STATES PATENT OFFICE.

BRUNO STECHBART, OF CHICAGO, ILLINOIS.

REVERSING-SWITCH.

1,399,411.

Specification of Letters Patent.

Patented Dec. 6, 1921.

Application filed May 12, 1919, Serial No. 296,368. Renewed January 22, 1921. Serial No. 439,318.

To all whom it may concern:

Be it known that I, BRUNO STECHBART, a citizen of the United States of America, and a resident of Chicago, in the county of Cook, State of Illinois, have invented certain new and useful Improvements in Reversing-Switches, of which the following is a specification.

This invention relates to reversing switches intended more especially for the smaller type of electric motors used as individual drivers for machines and mechanisms, and has for its object:—

To provide a semi-rotary reversing switch mechanism of the rapid make and break or snap type of a simple and effective structural formation and association of parts, and where with the starting, stopping and reversing of a motor can be readily effected, all as will hereinafter more fully appear.

In the accompanying drawing:—

Figure 1 is a plan view of the present reversing mechanism, with the operating shaft or handle shown in section.

Figs. 2 and 3 are companion end elevations from opposite ends of the mechanism, and illustrating the connections, etc., of the fixed contact members.

Fig. 4 is a detail sectional elevation on line 4—4, Fig. 5.

Fig. 5 is a longitudinal section on line 5—5, Fig. 1.

Fig. 6 is a detached perspective view of one of the pair of fixed contact members of the circuit inlet end of the mechanism.

Fig. 7 is a similar view of one of the pair of fixed contact members of the circuit outlet end of the mechanism.

Like reference numerals indicate like parts in the several views.

Referring to the drawing, 1 designates a main supporting base, usually of the plate form shown, and upon which the different elements of the mechanism are mounted.

2 designates the centrally arranged operating rock shaft of the mechanism, provided with the usual operating knob or handle 3 and journaled at its lower end in the base plate 1 and intermediate its length in a stationary bridge plate 4, now to be described.

4 designates the bridge plate above referred to and which is supported in spaced relation to the base 1 by a pair of end posts 5, preferably of the screw bolt form as shown. The bridge plate 4 is formed with

a central journal orifice for the rock shaft 2 aforesaid, with an upturned centrally arranged marginal stop lug 6, with a marginal recess 7 in opposed relation to said stop lug 6, and with longitudinally disposed guide slots 8 at the sides of its journal orifice, as shown more particularly in Fig. 1.

9 designates a combined operating and locking plate fixedly secured to the operating shaft 2, and disposed outside the bridge plate 4 and in adjacent relation thereto. The plate 9 is provided with a centrally arranged crank stud or lug 10 adapted for operative engagement with the hereinafter described snap or operating spring 19, and with a pair of circularly spaced arms 11 in equidistant angular relation to the crank stud 10. Said arms 11 are adapted to contact with the stop lug 6 of the bridge plate 4 to limit the rocking movement of the plate 9 in actual use, and said arms are provided with in-turned marginal flanges 12 for intermittent holding engagement with the hereinafter described sliding plate 16 associated with the movable contact members of the mechanism.

13 designates a crank disk fixedly associated with the movable contact members of the switch mechanism, and provided with a crank stud or lug 14 arranged in adjacent relation to the stud or lug 10 of the plate 9, for operative engagement with the spring 19 hereinafter described and having engagement in the marginal recess 7 of the fixed bridge plate 4, so as to be restricted in its rocking movement by the end shoulders of said recess.

15 designates a pin or stud on the crank disk 13 having operative engagement with the hereinafter described radial slot of a sliding head or plate 16, to cause the sliding head 16 and crank disk 13 to have movement in unison.

16 designates a sliding head or plate arranged between the crank disk 13 and the bridge plate 4 and having out-turned lugs 17 for guiding engagement with the guide slots 8 of said bridge plate and confined thereby to movement in a rectilinear path. The ends of the lugs 17 project through said slots so as to have a path in line with the in-turned flanges 12 of the rocking plate 9 for intermittent holding engagement therewith as set forth in the operation of the mechanism.

18 designates a radial slot in the plate or head 16 for operative engagement with the crank pin 15 of the crank disk 13 aforesaid.

19 designates the heretofore referred to snap or operating spring, having operative engagement with the stud or lug 10 of the operating plate 9 and with the corresponding 5 stud or lug 14 of the crank disk 13, with a resilient tendency to return and maintain said studs in a radially aligned condition. In the preferred form of the spring 19 the same comprises a circularly coiled body portion adapted to loosely encircle the operating shaft 2 of the mechanism, and a pair of crossed fingers or extensions 20 which straddle or embrace the studs or lugs 10 and 14 to resiliently hold the same in the described 10 15 radial alignment.

21 and 22 designate the respective inlet and outlet terminal posts or piles of the switch mechanism fixedly attached to the base 1 at opposite sides of the mechanisms 20 and parts above described. In the preferred construction shown in the drawing, each post or pile 21, 22, will consist of alternate strips of insulating material and a pair of metal strips 23, 24 or 25, 26 with each strip 25 formed with a terminal ear for its individual connection in the circuit, and with duplicate contact ears or lugs arranged in spaced relation and projecting into the path of a movable contact member of the mechanism. 30 In the present improvement one pair of strips 23, 24 will have a parallel relation to each other as shown in Fig. 2, while the other pair of strips 25, 26 will have a crossed relation to each other as shown in Fig. 3, 35 the object being to preserve the position of the positive and negative terminal points of the switch in line with each other.

27 and 28 designate the pair of movable contact members of the mechanism, secured 40 together at their middle portion and to the aforesaid crank disk 13, through interposed disks of insulating material, and having pivotal relation with the operating shaft 2 without electrical connection therewith. In 45 the preferred construction each movable contact member 27, 28 will consist of a pair of spring bars the outer ends of which have a flared formation and adapted to slide with yielding friction upon opposite sides of the 50 aforesaid contact ears or lugs of the fixed contact members of the mechanism with a view to preserve effective electrical contact during continued use.

The operation of the mechanism is as follows:

Assuming the parts to be in the circuit interrupted condition shown in Fig. 1, with the crank disk 13 held from a rocking movement in either direction by the engagement 60 of the lugs 17 of its associated sliding plate 16 against the inner faces of the holding flanges 12 of the operating plate 9.

In a manipulation of the parts to the left to establish the circuit on a motor or the like and attain a forward drive of the same,

the right hand end lug 17 of the sliding plate 16 has bearing against the inner face of the right hand flange 12 of the operating plate 9, and said sliding plate 16 is held from movement to the right, with the 70 stud or lug 14 of the associated crank disk 13 forming a stationary abutment for one of the fingers 20 of the spring member 19. Said holding movement prevails until a turning movement of the plate 9 to the left 75 carries its right hand flange 12 out of the path of the aforesaid right hand lug 17 to release the same and permit a sliding movement of the plate 16 to the right, and a turning movement to the left of the crank 80 disk 13 and the associated movable contact members 27, 28 into electrical contact with the right hand fixed contact members 23, 24, and left hand fixed contact members 25, 26, to complete the circuit and effect a forward 85 drive of an electric motor or the like. In this and the other manipulations of mechanism hereinafter set for the movement of the plate 16 and associated parts takes place in a rapid manner under the influence of 90 the spring member 19, the tension of which has been increased by the independent movement of the operating plate 9 and its spring actuating lug 10.

In a manipulation of the parts in an opposite direction, and to the right, to break the established circuit just described an initial turning movement of the plate 9 to the right, brings its right hand holding flange 12 into holding engagement with the inner face of the right hand lug 17 of the sliding plate 16, to hold the same and its associated parts from movement and in a locked condition until in the continued turning movement to the right of the plate 9 its right hand holding flange 12 moves out of the path of the aforesaid right hand lug 17 to release the same and permit a sliding movement of the plate 16 to the left, and a turning movement to the right of the parts operatively associated with the plates 9 and 100 110 16 to effect a break in the electric circuit.

In a manipulation of the parts to attain a reversal in the direction of the current to a motor or the like, the turning movement of the plate 9 to the right is continued, and an initial movement of said plate 9 brings its left hand holding flange 12 into holding engagement with the outer face of the left hand lug 17 of the sliding plate 16 to hold the same in a similar locked condition to that above described, until in a continued turning movement to the right of the plate 9, its described left hand holding flange 12 125 moves out of the path of the aforesaid left hand lug 17 to release the same and permit a sliding movement of the plate 16 to the left and a turning movement to the right of the crank disk 13 and the associated 130

movable contact members 27, 28 into electrical contact with the left hand fixed contact members 23, 24 and right hand fixed contact members 25, 26 to complete the electrical circuit and attain a reverse drive of an electric motor or the like.

In the present switch mechanism, the co-acting lugs 17 of the sliding plate 16 and holding lugs 12 of the operating plate 9 confine the parts to a predetermined degree of rocking motion in actual use. It is preferable however to provide separate means for attaining in a more substantial manner such restriction of movement, to wit: the 15 marginal recess 7 and marginal stop lug 6 heretofore described.

Having thus fully described my said invention what I claim as new and desire to secure by Letters Patent, is:—

20 1. In a reversing switch, the combination of an operating plate, means for imparting a rocking movement to said plate, a pair of rocking contact arms moving in unison and insulated from each other, pairs of fixed 25 contact members individual to the rocking contact arms aforesaid, and an operative connection between said rocking contact arms and the aforesaid operating plate, comprising a sliding head operatively connected 30 to said rocking contact arms, means for confining said sliding head to movement in a rectilinear path, means between said sliding plate and the operating plate for locking said sliding plate at each end of its path and 35 at the middle of said path, and a spring associated with said rocking contact arms and the operating plate for imparting a snap movement to said arms when the sliding plate is released from either of the aforesaid holding engagements, with the operating 40 plate, substantially as set forth.

2. In a reversing switch, the combination of an operating plate, means for imparting a rocking movement to said plate, a pair of 45 rocking contact arms moving in unison and insulated from each other, pairs of fixed contact members individual to the rocking contact arms aforesaid, and an operative connection between said rocking contact 50 arms and the aforesaid operating plate, comprising a sliding head operatively connected to said rocking contact arms by a crank disk and radial slot connection, means for confining said sliding head to movement in a rectilinear path, means between said sliding plate and the operating plate for locking said sliding plate at each end of its path and at the middle of said path, and a spring 55 associated with said rocking contact arms and the operating plate for imparting a snap movement to said arms when the sliding plate is released from either of the aforesaid holding engagements with the operating plate, substantially as set forth.

60 3. In a reversing switch, the combination

of an operating plate, means for imparting a rocking movement to said plate, a pair of rocking contact arms moving in unison and insulated from each other, pairs of fixed contact members individual to the 70 rocking contact arms aforesaid, and an operative connection between said rocking contact arms and the aforesaid operating plate, comprising a sliding head operatively connected to said rocking contact arms, 75 means between said sliding plate and the operating plate for locking said sliding plate at each end of its path and at the middle of said path, the same comprising marginal flanges on the operating plate and lugs on the 80 sliding plate adapted for intermittent engagement with said marginal flanges, and a spring associated with said rocking contact arms and the operating plate for imparting a snap movement to said arms when the 85 sliding plate is released from either of the aforesaid holding engagements with the operating plate, substantially as set forth.

4. In a reversing switch, the combination of an operating plate, means for imparting a rocking movement to said plate, a pair of rocking contact arms moving in unison and insulated from each other, pairs of fixed contact members individual to the rocking contact arms aforesaid, and an operative 90 connection between said rocking contact arms and the aforesaid operating plate, comprising a sliding head operatively connected to said rocking contact arms, means for confining said sliding head to movement in a 95 rectilinear path, means between said sliding plate and the operating plate for locking said sliding plate at each end of its path and at the middle of said path, a crank pin or lug associated with the rocking contact 100 arms, a companion pin or lug on the operating plate, and a spring having arms or extensions straddling said pins and tending to maintain the same in a radial alignment, substantially as set forth.

110 5. In a reversing switch, the combination of an operating plate, means for imparting a rocking movement to said plate, a pair of rocking contact arms moving in unison and insulated from each other, pairs of fixed 115 contact members individual to the rocking contact arms aforesaid, and an operative connection between said rocking contact arms and the aforesaid operating plate, comprising a sliding head operatively connected to said rocking contact arms by a crank disk and radial slot connection, means for confining said sliding head to movement in a rectilinear path, means between said sliding plate and the operating plate for locking 120 said sliding plate at each end of its path and at the middle of said path, a crank pin or lug associated with the rocking contact arms, a companion pin or lug on the operating plate, and a spring having arms or ex- 125

130

tensions straddling alinement, substantially as set forth.

6. In a reversing switch, the combination of an operating plate, means for imparting a rocking movement to said plate, a pair of rocking contact arms moving in unison and insulated from each other, pairs of fixed contact members individual to the rocking contact arms aforesaid, and an operative connection between said rocking contact arms and the aforesaid operating plate, comprising a sliding head operatively connected to said rocking contact arms, means between said sliding plate and the operating plate for locking said sliding plate at each end of its path and at the middle of said path, the same comprising marginal flanges on the operating plate and lugs on the sliding plate adapted for intermittent engagement with said marginal flanges, a crank pin or lug on the crank disk aforesaid, a companion pin or lug on the operating plate, and a spring having arms or extensions straddling said pins and tending to maintain the same in radial alinement, substantially as set forth.

7. In a reversing switch, the combination of an operating plate, means for imparting a rocking movement to said plate, a pair of rocking contact arms moving in unison and insulated from each other, pairs of fixed contact members individual to the rocking contact arms aforesaid, one pair of said fixed contact members having parallel relation to each other and the other pair of said members a crossed relation to each other, an operating connection between the rocking contact arms and operating plate aforesaid, comprising a sliding head opera-

tively connected to said rocking contact arms, means between said sliding plate and the operating plate for locking said sliding plate at each end of its path and at the middle of said path, and a spring associated with rocking contact arms and the operating plate for imparting a snap movement to said arms when the sliding plate is released from either of the aforesaid holding engagements with the operating plate, substantially as set forth.

8. In a reversing switch, the combination of an operating plate, means for imparting a rocking movement to said plate, a pair of rocking contact arms moving in unison and insulated from each other, pairs of fixed contact members individual to the rocking contact arms aforesaid, one pair of said fixed contact members having parallel relation to each other and the other pair of said members a crossed relation to each other, an operating connection between the rocking contact arms and the operating plate aforesaid, comprising a sliding head operatively connected to said rocking contact arms by a crank disk and radial slot connection, means between said sliding plate and the operating plate for locking said sliding plate at each end of its path and at the middle of said path, and a spring associated with said rocking contact arms and the operating plate for imparting a snap movement to said arms when the sliding plate is released from either of the aforesaid holding engagements with the operating plate, substantially as set forth.

Signed at Chicago, Illinois, this 30th day of April, 1919.

BRUNO STECHBART.
